PORTABLE HOUSING STRUCTURE

John H. Mosier, Cedar Lake, Ind.

Application March 21, 1958, Serial No. 722,882

6 Claims. (Cl. 4—172)

This invention relates to a portable housing structure and more particularly to a portable housing structure which may be used as a houseboat, as a house trailer when mounted on a carriage, as a bath house when adjacent a swimming pool, and as a garage or other structure when mounted on top of a swimming pool or similar supporting framework.

Portable boats which may be transported overland on trailers of various types have been in use for some time. However, none of these structures have been adaptable to use as house trailers as the construction of the hull of the boats makes their use as house trailers impractical.

The present invention is directed to a housing structure which may be used as both a houseboat and a house trailer, being so constructed as to be mounted on a carriage in a manner which makes the housing structure practical as a house trailer.

The popularity of private swimming pools has increased greatly in recent times. Many family homes have back yard swimming pools where area permits. However, as swimming pools require considerable area, very often the home owner will decide against a swimming pool because there is not room in his yard.

The present invention provides a portable housing structure which may be mounted over a swimming pool in cold weather so as to serve as a garage or other useful structure. With this arrangement, the area normally occupied by the garage can be utilized in the summer time as a swimming pool, and in the winter time the housing structure can be mounted over the pool and used as a garage. Since the swimming pool is only desirable in summer months, when a garage is relatively unimportant, this arrangement provides a very satisfactory space saving advantage.

Thus, the present invention provides a portable housing structure which may be used as a boat, which is adaptable to a carriage to form a house trailer and which is adaptable to mount over a swimming pool to form a garage or similar structure.

Other and further advantages and features of the present invention will be apparent from the following description and drawings in which:

Fig. 1 is a perspective view of a portable housing construction illustrating one embodiment of the present invention wherein the portable housing structure is mounted on a carriage parked adjacent a swimming pool;

Fig. 2 is a top plan view of the structure of Fig. 1;

Fig. 3 is a top plan view of the structure of Fig. 1 with the portable housing structure positioned over the swimming pool;

Fig. 4 is a vertical sectional view taken along line 4—4 of Fig. 3;

Fig. 5 is an exploded perspective view of the means for latching the carriage to the pool illustrated in Fig. 4;

Fig. 6 is a side elevational view of the portable housing structure of Fig. 1 broken away and illustrating the side of the carriage or the side of the pool in dot-dash lines;

2

Fig. 7 is a side elevational view partially in section of the structure of Fig. 1 showing the portable housing structure in an intermediate position;

Fig. 8 is a top plan view of an alternate embodiment of the present invention wherein the portable housing structure of Fig. 1 is used with an enlarged pool and a second housing structure;

Fig. 9 is a side elevational view of the portable housing structure of Fig. 1 mounted on a pool, which is in section, and being utilized as a garage;

Fig. 10 is a vertical sectional view of the portable housing structure of Fig. 9 shown with the rear wall partially raised and the intermediate partition pivoted to the horizontal position;

Fig. 11 is an enlarged exploded view partially broken away of the slot and pin means for guiding the movement of the rear wall of the structure of Fig. 10;

Fig. 12 is a top plan view of the hull portion of the portable housing structure of Fig. 1;

Fig. 13 is a vertical sectional view taken along line 13—13 of Fig. 12 and illustrating an outboard motor in dotted lines;

Fig. 14 is a vertical sectional view taken along line 14—14 of Fig. 12;

Fig. 15 is a perspective view of the portable housing structure of Fig. 1 being used as a houseboat in a lake;

Fig. 16 is a vertical sectional view of the second housing structure of Fig. 8 shown in position over the pool; and

Fig. 17 is a front elevational view of the structure of Fig. 16 with the pool shown in section.

Referring now to the drawings, the construction of the present invention will be described in detail. The basic unit of the present invention is the portable housing construction 20 which is shown in the drawings in its various capacities as a house trailer, houseboat, bath house and garage. This housing structure consists of a hull 21 of rectangular outline having inwardly sloping front 22 and rear 23 faces and a flat bottom 24. A platform 25 is secured across the top of the hull and extends outwardly on all four sides thereof. This platform 25 serves as the floor of the housing upon which the superstructure is constructed. The general construction of the superstructure may be of any desired design, and in the construction illustrated consists of side walls 26 extending upwardly from a position flush with the outer edges 27 of the sides of the platform 25 so as to provide a maximum interior area between walls 26. The front wall 28 of the housing extends upwardly from a position flush with the front edge 29 of the platform 25 and has a generally curved upper portion 30 which curves rearwardly and blends into the roof 31 of the housing to give a smooth streamlined effect to the front of the housing. The roof 31 extends the full length of the housing and is supported by the side walls 26 and by vertical posts 32 extending from the rear corners of the platform 25. The side walls 26 extend rearwardly from the front wall 28 to points spaced from the rear of the platform 25 so as to provide an open deck area at the rear of the housing.

A retractable rear wall 33 extends between the rear ends of the side walls 26. This rear wall 33 is movably mounted so that it may be removed to provide an opening between the ends of the side walls when it is desired to provide an open interior in the housing structure. In the embodiment illustrated, the end wall construction 33 is similar to a conventional garage door which slides up into a position along the ceiling of the garage. The particular construction illustrated consists of L-shaped channels 34 on the inside of each side wall 26 having vertical portions 35 extending vertically from the platform 25 to the roof 31 and horizontal portions 36 extending horizontally forward from the top of the vertical portion 35 a distance substantially equal to the

height of the rear wall 33. The channels 34 are generally rounded at the juncture 37 of the horizontal and vertical portions to facilitate manipulation of the rear wall. The rear wall 33 is provided with lateral pins 38 extending outwardly from each corner. These pins 38 extend into the channels 33 so as to guide the movement of the door upwardly and horizontally into a position along the roof 31 of the housing. The pins 38 have enlarged outer ends which are locked in the channels by lips 40 of the channel 33 extending partially across the channel openings. Thus, the rear wall can easily be manipulated from a lowered position to an upper position as desired.

In order to permit utilization of the housing structure 20 as a garage, the partitions which may be desirable when utilizing the structure as a house must be removable. One manner of accomplishing this is illustrated in the drawings wherein the intermediate partition 41 is hingedly secured to the roof 31 so that it may be swung from its normal vertical position into a horizontal position along the roof of the structure.

As seen in the drawings, the roof 31 of the housing structure 20 may be utilized as a sundeck in which case it is desirable to provide a railing 42 around the edge of the roof to prevent passengers from falling therefrom, especially when the structure is used as a houseboat. Also the rear end of the roof may be utilized as a diving platform, having a diving board 43 extending rearwardly therefrom. This diving board can be used when the structure is afloat and also can be used when the structure is parked adjacent the swimming pool 44 as seen in Fig. 1. Access to the roof 31 may be had through an opening 45 at the rear which is connected by a ladder 46 to the platform 25.

In order to insure floatability of the housing structure, the hull portion 21 is provided with front and rear airtight compartments 47 and 48 which may be sealed with air or other gas to impart the desired buoyancy to the complete structure. The hull is strengthened by using cross braces 49 secured therein and extending across the interior of the hull. In the embodiment illustrated there are three sets of cross braces 49 interposed between the airtight compartments 47 and 48. The airtight compartments occupy approximately the front and rear quarters of the hull. The periphery of the platform also reinforces the hull strength. The center portion 50 of the platform is formed separate from the periphery so that it may be removed to gain access to the interior of the hull 21.

The rear of the hull is provided with a centrally located motor mounting compartment 51 to receive an outboard motor 52 of any conventional design. This compartment 51 is recessed into the rear airtight compartment as at 53 and has a rear wall 54 extending upwardly from the bottom 24 of the hull 21 at a point spaced forwardly of the rear 23 of the hull. This rear wall 54 serves as a mounting upon which the motor 52 is attached as by locking brackets or other conventional construction. The motor extends into the compartment 53 and the shaft of the motor extends through the opening 55 in the hull which is provided rearwardly of the rear wall 54 of the compartment. The shaft 56 extends downwardly below the bottom 24 of the hull so that the propeller 57 of the motor will be located in the water for efficient propulsion of the boat. The size of the compartment 51 is such that the motor can be pivoted thereinto when out of use so that the propeller will be pivoted upwardly above the bottom of the hull. A covering plate 58 is secured over the top of the compartment 51 and hull opening 55 so that when the motor is not mounted therein, the plate 58 will form a flush continuance of the platform 25 for use as a floor or deck.

The carriage 60 upon which the housing structure 20 of the present invention is mounted consists of a framework braced in any desirable manner suitable to pro-

vide sufficient strength for supporting and transporting the housing structure 20 when mounted thereon. In the embodiment illustrated, the carriage 60 consists of pairs of wheels 61 mounted on each side of the carriage and a front smaller wheel (not shown) which is retractable during movement of the carriage and is lowerable to support the front end when the carriage is parked. The front end 62 of the carriage 60 is provided with a hitch 63 of any conventional construction which is attachable to a complementary hitch on the rear of a motor vehicle. Also mounted at the front 62 of the carriage is a winch 64 which may be mechanically operated or manually operated by the crank 65 as illustrated. The winch 64 has a horizontal axis upon which a rope 66 or chain is wound. The outer end of the rope or chain is connected to an eye 67 secured to the front of the housing structure so that the housing structure 20 may be pulled onto the carriage 60 and held in place on the carriage by the tension in the rope or chain.

The framework of the carriage consists of bottom cross braces 68 extending between longitudinal bottom stringers 69. The front ends of the bottom stringers 69 are supported by a front cross piece 70 and diagonal front braces 71. Top longitudinal stringers 72 are spaced above the bottom stringers 69 by vertical braces 73. Each top stringer 72 has a front wheel well 74, a rear wheel well 75, and an intermediate wheel well 76. Each of these wheel wells extends partially across the stringer 72 from the inside edge of the stringer so that each wheel well has an outer side 77 and a bottom 78. The bottoms 78 are arcuate with sharply curved forward portions and sloping rear portions which blend into the tops of the stringers 72 so as to smoothly receive and stop the wheels of the housing structure.

The housing structure 20 is provided with six wheels, each side of the housing structure having a front wheel 79, an intermediate wheel 80 and a rear wheel 81. The wheels are mounted in the underside of the edges 27 of the platform 25 which extend beyond the hull 21. These wheels 79, 80 and 81 are aligned with the wheel wells 74, 75 and 76 formed in the carriage and are similarly spaced so that when the housing structure 20 is fully mounted on the carriage 60 the wheels will be seated in the wells and the side edges 27 of the platform 24 of the housing will be in contact with and be supported by the top stringers 72 of the carriage. The outer sides 77 of the wheel wells prevent lateral movement of the housing structure with respect to the carriage and the hull 21 extending into the area between the sides of the carriage also limits lateral movement of the housing structure. In the embodiment illustrated, the bottom 24 of the hull 21 does not rest on the bottom of the carriage 60 when fully mounted thereon, the entire weight of the structure being supported by the top stringers 72.

The primary purpose of the wheels 79, 80 and 81 is to provide rolling support of the housing structure 20 so that the housing structure may be rolled onto and off the carriage 60. Thus as the housing structure is pulled onto the carriage, the wheels contact the top stringers 72 and support the housing until the housing has been rolled fully onto the carriage in which position the wheels 79, 80 and 81 will be in the wheel wells 74, 75 and 76 and the housing 20 will be supported by the platform 25 resting on the top stringers 72. As stated above, the housing 20 is held on the carriage 60 by the winch 64 and can be further secured thereon by using a tie rod (not shown) or other means to pull the rear ends of the stringers 72 toward each other against the hull 21 of the housing to lock it in place.

When the present housing structure 20 is utilized in conjunction with a swimming pool 44 as illustrated in

Fig. 1, the longitudinal sides 82 of the swimming pool are provided with wheel wells 83, 84 and 85 resembling the wells 74, 75 and 76 on the carriage 60. These wells are similarly formed to extend partially across the pool sides from the inside of the side walls and have similarly curved bottoms 86 inclined to blend into the tops 87 of the pool sides 82 for the smooth receipt of the wheels of the housing structure 20. One end 88 of the pool is provided with a removable end plate 89 extending across the end of the pool and having a depth substantially the same as the depth of the hull 21 of the housing structure 20. This plate is normally sealed in place as seen in Fig. 4 so as to complete the end of the swimming pool, but is removable to permit the housing structure to roll into position over the pool as seen in Fig. 7. The housing structure 20 may be drawn from the carriage 60 onto the pool as by a rope or chain wound on a winch 90 attached to the other end 91 of the pool 44 in a manner similar to the operation of mounting the housing structure 20 on the carriage 60. Thus, the housing structure rolls on the wheels 79, 80 and 81 until fully on the swimming pool 44 at which time the wheels roll into the wheel wells 83, 84 and 85 and the structure is supported by the edges 27 of the platform 25 resting on the tops 87 of the walls 82 of the swimming pool 44. In this position the structure may be used as a garage or for any other purpose, and the swimming pool is covered to protect it from the weather as well as for safety reasons to prevent children and others from falling into the pool.

When the swimming pool is in use, it may be desirable to have smooth pool edges in which case the wheel wells 83, 84, and 85 may be enclosed by inserting fillets (not shown) therein and when the housing is mounted on the pool, the fillets may be inserted in the carriage wheel wells 74, 75, and 76 so that the carriage will resemble an all-purpose trailer.

As described above, two winches are provided: one winch 64 mounted on the carriage and the other winch 90 mounted on the swimming pool. If desired, a single winch can be utilized that is interchangeable from the pool to the carriage by the simple expedient of detachable brackets or other means permitting removal of the winch.

In the embodiment illustrated a carriage driveway 92 is provided extending from the rear end 88 of the pool 44. This driveway 92 is recessed so that its surface is spaced a distance below the top of the pool equal to the height of the top stringers 72 of the carriage 60 from the ground so that when the carriage is adjacent the pool, the top stringers 72 will be on the same level as the tops 87 of the pool walls to permit easy movement of the housing structure 20 from one to the other. In order to align the carriage 60 with the pool 44, the present invention provides a flange 93 and slot 94 attachment of the carriage to the swimming pool. The ends of the top stringers 72 of the carriage are provided with rearwardly extending horizontal flanges 93 located below the tops of the stringers, and the ends 95 of the swimming pool sides 82 extend rearwardly and are provided with slots 94 aligned to receive the flanges 93 so that when the carriage is backed into position, the flanges will engage in the slots. The flanges 93 are provided with central holes 96 and the portions of the swimming pool 44 adjacent the slots 94 are similarly provided with holes 97 for the receipt of a locking pin 98 which drops through the holes 96 and 97 to lock the carriage 60 to the swimming pool 44. This fixes the position of the carriage with respect to the pool and prevents the carriage from moving.

The carriage driveway 92 is seen in Fig. 4 to have a cutout portion 99 adjacent the pool with steps 100 leading down thereto. The pool 44 is provided with a watertight door 101 adjacent the cutout portion 99 so that access may be had to the pool, which may be desirable when the housing structure is mounted on the pool,

in which case the pool can be used as a storage area or storm shelter.

In the event a larger size swimming pool 102 is desired, the present embodiment may be varied as seen in Figs. 5, 8, 16 and 17 without affecting the construction of the portable housing structure 20 itself. Since the housing structure, when used as a house trailer, must be limited in width to conform to the statutory maximum vehicle widths, a second housing structure 103 may be utilized with the large pool. This second housing structure 103 is slideable from a position covering a portion of the pool to a position adjacent the pool. When both structures 20 and 103 are removed from the pool 102, the entire pool area can be used as a swimming pool with the sliding structure 103 located adjacent one side 104 of the pool and used as a bathhouse or for any other desired purpose. The sliding structure 103 has front and rear flanges 105 which overlay the corresponding ends 106 of the pool so that the sliding structure 103 will be supported by the ends 106 of the pool when it has been slid over the pool. The side 107 of the sliding structure 103 adjacent the pool has an outwardly extending ledge 108 with its top surface 109 flush with the top of the pool ends 106 so that when the sliding structure is slid into position over the pool, the ledge 108 will be in the same position as the sides of the pool in the small pool embodiment, for receipt of the wheels and platform edges of the portable housing, this is shown in dot-dash lines in Fig. 8. This ledge 108 is provided with wheel wells 110 similar to and aligned with the wheel wells 111 on the other side of the pool.

The under side of the sliding structure 103 is provided with a pair of legs 112 which are pivotally attached under the side 107 of the structure adjacent the pool 102. These legs 112 are of a length equal to the depth of the pool so that when they are pivoted into their vertical positions, they will serve as support legs to support not only the side of the sliding structure 102 but also the side of the portable structure 20 which rests on the ledge 108 of the sliding structure. These legs are pivotally secured to the underside of the sliding structure so that they may be swung to horizontal positions under the sliding structure where they are hidden and out of the way when the pool is used for swimming purposes. The horizontal leg positions are shown in dot-dash lines in Fig. 17.

The sliding structure 103 must be of a width at least equal to the width of the pool not covered by the portable structure 20 so that when both structures are mounted on the pool, the pool will be completely enclosed for safety and protective reasons. The far side of the sliding structure 103 is provided with a depending bar 114 which engages the outer side 115 of the pool edge 104 to stop the sliding of the structure 103 and properly position the structure so that the ledge 108 is in line with the wheels 79, 80 and 81 of the portable structure 20.

Thus, with the variation above described the portable housing structure 20 can be utilized with a pool 102 of a width greater than the width of the portable housing structure. A sliding structure 103 is also provided which is adaptable for use both as a bathhouse or other structure adjacent the pool and as a covering structure over the pool when the pool is not in use. This provides additional flexibility and also permits the enlargement of the pool to a desired width limited only by the sum of the widths of the portable and sliding structures.

While this invention is susceptible of embodiments in many different forms, there is shown in the drawings and is herein described in detail several embodiments with the understanding that the present disclosure is to be considered as an exemplification of the principles of the invention, and is not intended to limit the invention to the embodiments illustrated. The scope of the invention will be pointed out in the appended claims.

I claim as my invention:

1. A housing structure comprising: a housing having sides and rotatable members mounted in said sides and depending therefrom adjacent the housing; a swimming pool having parallel sides; a supporting framework having parallel sides alignable with the sides of the swimming pool, the pool sides and framework sides being alignable with the housing sides and having top surfaces upon which said rotatable members may be supported to permit rolling of the housing along the framework, along the pool and from one to the other, said pool sides and framework sides having wells extending downwardly from the top surfaces into which said rotatable members may roll to seat the housing on the framework or swimming pool.

2. A housing structure comprising: a housing having a hull portion and a platform secured across the top of the hull portion, said platform having parallel sides extending beyond the hull portion; wheels secured in and depending from said platform sides; a swimming pool having parallel sides spaced to receive the housing wheels and sides with the hull portion depending between the swimming pool sides; a supporting carriage having parallel sides spaced to receive the housing wheels and sides and alignable with the swimming pool sides, said pool sides and carriage sides having top surfaces upon which said wheels may be supported to permit rolling of the housing along the carriage, along the pool and from one to the other, said pool sides and carriage sides having wheel wells extending downwardly from the top surfaces a depth at least equal to the distance the wheels depend from the platform sides, said wells accommodating said wheels so that when the wheels are in the wells the carriage sides or pool sides engage the platform sides to seat the housing on either of the carriage and pool with the housing hull between the carriage and pool sides respectively.

3. A housing structure comprising: a housing having parallel sides and rotatable members mounted in and depending from said sides; a swimming pool having a side and a supporting member extending across the pool parallel to the pool side and spaced therefrom for receipt of the housing sides on the pool side and supporting member, said pool side and supporting member having top surfaces and wells extending downwardly from the top surfaces into which said rotatable members roll to seat the housing on the pool and supporting members.

4. A portable housing structure mountable on a swimming pool, comprising: a first housing having parallel sides and rotatable members mounted in and depending from said sides; a swimming pool having a side; a second housing mountable over a portion of the pool and having an outwardly extending ledge parallel to the pool side and spaced therefrom for receipt of the first housing sides on the pool side and ledge, said pool side and ledge having top surfaces and wells extending downwardly from the top surfaces into which said rotatable members roll to seat the first housing on the pool and ledge.

5. A portable housing structure mountable on a carriage and movable from the carriage onto a swimming pool, comprising: a housing having a hull portion and

10 a platform secured across the top of the hull portion, said platform having parallel sides extending beyond the hull portion; wheels secured in and depending from said platform sides; a swimming pool having a side; a supporting member removably mounted across the pool parallel to the pool side and spaced therefrom for receipt of the platform sides on the pool side and supporting member; a supporting carriage having parallel sides spaced to receive the housing wheels and sides and alignable with the swimming pool side and supporting member, said pool side, supporting member and carriage sides having top surfaces and wheel wells extending downwardly from the top surfaces a depth at least equal to the distance the wheels depend from the platform sides, the top surfaces supporting the wheels for rolling of the housing along the carriage, over the pool and from one to the other, the wells accommodating the wheels so that when the wheels are in the wells the top surfaces engage the platform sides to seat the housing on either the carriage or pool and supporting member with the housing hull between the carriage sides or between the pool side and supporting member.

20 15 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000
